UNITED STATES PATENT OFFICE.

JAMES S. MERRITT, OF PHILADELPHIA, PENNSYLVANIA, ASSIGNOR TO THE MERRITT & COMPANY, OF SAME PLACE.

FIREPROOF CEILING, ARCH, &c.

SPECIFICATION forming part of Letters Patent No. 664,879, dated January 1, 1901.

Application filed September 15, 1899. Serial No. 730,529. (No model.)

To all whom it may concern:

Be it known that I, JAMES S. MERRITT, of the city and county of Philadelphia, in the State of Pennsylvania, have invented an Improvement in Fireproof Ceilings, Arches, &c., of which the following is a specification.

My invention has reference to fireproof ceilings or arches; and it consists of the improvements which are fully set forth in the following specification and are shown in the accompanying drawings.

More particularly my invention relates to that class of fireproof ceilings or arches which consists of a combination of metallic lathing and cement or plastic material in which the lathing is embedded. It is desirable in some ceilings and arches of this character that the lathing should be thoroughly embedded in the plastic material with a substantial layer of plastic material on the lower side. Where such ceilings and arches are constructed with centering, means must be provided for elevating the body of the lathing above the surface of the centering to provide space for the formation of the layer of concrete or cement below the body of the lathing. In some cases the centering has been provided with projections or offsets to hold its surface away from the lathing to the desired extent; but such methods are objectionable, as the offsets or projections form holes or openings in the concrete, which must afterward be filled up. This requires additional labor, and such arches or ceilings must be carefully plastered or finished on the lower surface after the centering is removed. It has also been proposed to provide the lathing with offsetting projections, which rest upon the centering and hold the body of the lathing at the desired elevation; but such methods are also highly objectionable, because such lathing is more expensive and difficult to make, and when the centering is removed the offsetting portions of metal which rested upon the centering are exposed and not covered by cement, and the arch must be plastered and finished at additional expense and labor.

It is the object of my invention to accomplish the offsetting of the lathing from the centering without these difficulties or objections, and to this end I employ a series of

loose offsetting blocks or pieces arranged between the lathing and centering, which become embedded and incorporated in the cement or plastic material. By making these 55 blocks or pieces of cement or concrete or of whatever material is used in the construction of the floor their presence when the centering is removed is rendered entirely unobjectionable, and they become actually incorporated 60 in the body of the cement or concrete and form with it a homogeneous mass presenting a smooth intrados or surface which need not be further plastered or finished except for 65 purely decorative purposes.

My invention is illustrated in the accompanying drawings, in which—

Figure 1 is a transverse vertical sectional view of a fireproof ceiling embodying my invention. Fig. 2 is a similar view, enlarged, 70 of a portion of the same, omitting the concrete or plastic material; and Fig. 3 is a perspective view of one of the offsetting-blocks.

I are the beams between which the arch or floor is formed.

A is a sheet of metallic lathing, which may be of any suitable character, such as expanded metal.

B is a centering such as is commonly used in the construction of arches.

C are the offsetting blocks or pieces, preferably formed of concrete or cement.

In constructing an arch or ceiling the centering B is first put in place and the blocks and pieces C are placed upon it and disposed over the surface in suitable number and proper location. The lathing A is then laid on, extending from beam to beam and resting upon the blocks or pieces C, which act to hold the lathing out of contact with the centering and elevated a slight distance above it. The plastic material or concrete D is poured on the lathing, and the lower portion passes through the interstices thereof and forms a layer below, thoroughly embedding the body of the lathing. The offsetting-blocks C are also embedded in the concrete and become fixed and incorporated therein, and as they are preferably formed of cement or concrete they become practically a portion of the concrete or cement body of the arch. When the concrete has hardened or set, the centering is removed.

The blocks or pieces C may be formed in any convenient shape, that shown consisting of an inverted frustum of a cone, being preferably used because it permits the cement or 5 concrete to become easily packed around the block and thus to more effectively fix and hold the block in place.

While I have illustrated my invention as applied to a curved arch, it is equally applicable to flat arches and flat ceilings, floors, and partitions.

The details of construction may be varied without departing from the invention.

What I claim as new, and desire to secure 15 by Letters Patent, is as follows:

1. An arch, ceiling, &c., consisting of a body of metallic lathing, a series of small independent supporting-blocks wholly separate from and unconnected with the lathing but 20 acting to support it during the formation of the arch, and a body of plastic material embedding said lathing and supporting blocks or pieces in the lower layer of the plastic material below the lathing.

25 2. An arch, ceiling, &c., consisting of a body of metallic lathing, a series of small independent supporting-blocks formed of cement or concrete wholly separate from and unconnected with the lathing but acting to support 30 it during the formation of the arch, and a

body of plastic material embedding said lathing and supporting blocks or pieces in the lower layer of the plastic material below the lathing.

3. In an arch or ceiling construction, the 35 combination of a centering, a body of metallic lathing arranged above the centering, a body of plastic material embedding said body of metallic lathing, offsetting-pieces formed of the same material as the body of plastic material, arranged below the centering and acting to offset the lathing from the surface of the centering and embedded with said lathing in said body of plastic material.

4. In an arch or ceiling construction, the 45 combination of a centering, a body of metallic lathing arranged above the centering, a body of plastic material embedding said body of metallic lathing, offsetting-pieces formed of plastic material, arranged below the centering and acting to offset the lathing from the surface of the centering and embedded with said lathing in said body of plastic material.

In testimony of which invention I have 55 hereunto set my hand.

JAMES S. MERRITT.
